GROVER S. EBLE, OF NEW YORK, N. Y., ASSIGNOR TO FRITZ ZIEGLER, JR., OF NEW YORK, N. Y.

MIXING VALVE.

Application filed October 26, 1922. Serial No. 596,957.

My present invention relates to valves for controlling the flow and the mixing of different fluids, and particularly to valves connected with a cold water supply and with a 5 hot water supply and adapted to deliver either cold water alone or hot water alone, or a mixture of both in variable proportions. The object of my invention is to provide a 10 very efficient apparatus of this class which will afford special facilities for assembling, dismembering, and adjusting the parts, together with other advantages which will appear from the detailed description following hereinafter.

Without intending to restrict myself to the particular constructions illustrated, I will now explain two satisfactory embodiments of my invention as shown in the accompanying drawings, in which Fig. 1 20 is a central section through one form of my invention, taken on line 1—1 of Fig. 4, with parts broken away, and showing the valve fully closed; Figs. 2 and 3 are partial sections, on the same plane 25 as Fig. 1, but Fig. 2 shows the valve in a partly open position in which it delivers cold water only, while Fig. 3 shows the valve opened to a greater extent so as to discharge a mixture of hot water and cold 30 water; Fig. 4 is a section on line 4—4 of Fig. 1; Fig. 5 is a perspective view of one of the valve parts; Fig. 6 is a section on line 6—6 of Fig. 1, with parts broken away; Fig. 7 is a detail axial section of one of the parts; 35 Fig. 8 shows another form of my invention, in a section taken on line 8—8 of Fig. 10 and corresponding to Fig. 1; Figs. 9, 10, and 11 are sections on lines 9—9, 10—10, and 11—11 respectively of Fig. 8; and Fig. 12 is 40 a perspective view of one of the parts of the mechanism.

In the drawings, the axis of the valve is shown vertical, and for the sake of convenience I have used terms such as "upper" and 45 "lower" in describing the relation of certain parts; it will be understood, however, that the valve may be used in any desired position.

The device illustrated in Figs. 1 to 7 comprises a lower casing member 20 provided in its upper portion with a cylindrical recess or chamber surrounded by an internally threaded wall or flange 21, at the bottom of which is arranged a plane (horizontal) wall

or partition 22. Below this partition are 55 three compartments 23, 24, 25 separated by vertical partitions 26, 27, 28 which extend downwardly from the partition 22 to the bottom wall of the casing member 20, a cylindrical wall 29 reaching from said bottom 60 wall to the partition 22, thus forming a pocket or well 30 open at the top. The two compartments 23, 24, which in the construction shown are of the same size and symmetrical to the plane of the partition 27, 65 are inlet compartments communicating with spuds 31, 32 respectively, one of these serving for the supply of cold water, and the other for hot water. In the drawings, it has been assumed that the spud 31 is connected 70 with the supply of cold water, and the spud 32 with the supply of hot water. The spuds may be threaded externally or internally for proper connection with the water supply, internal threads being shown. The 75 partition or wall 22 is provided with two preferably segmental through openings 33, 34 which are of the same shape and placed symmetrically with respect to the plane of the partition 27. On its outer side, each 80 opening 33, 34 is provided with an extension 35, 36 respectively, in a diameter corresponding to that in which the diametrically opposite spuds 31, 32 are located. A 85 third spud, 37, is located at right angles to the other two, and communicates with the third compartment, 25, which is the outlet compartment and has been shown somewhat smaller than the inlet compartments, although this is not necessary. 90

On the upper face of the partition 22 is set the valve-seat disk 38 having a central port 39 which communicates with a recess 40 provided in the lower face of said disk, said recess extending in a substantially radial 95 direction and being adapted to communicate at its outer end, with either of the openings 33, 34. In the position shown (see particularly Fig. 6), the recess 40 communicates with the opening 33, and therefore with the compartment 23 and with the spud 31. The disk 38 is further provided with segmental ports 41, 42, of which the former communicates with the opening 34 and therefore with the compartment 24 and spud 32, while the port 42 registers with a segmental opening 43 in the partition 22, and is connected, through such opening, with the outlet com- 100 105

partment 25 and spud 37, the latter being connected in any suitable manner with the shower or other device which is to discharge cold or hot water, or a mixture of both.

5 The disk 38 is pressed against the partition 22 by the shoulder 44 at the upper end of a cylindrical flange 45 located at the lower end of the upper casing member 46, said flange screwing into the threaded flange 21 of the lower casing member 20.

10 The disk 38 is provided with diametrically-opposite holes through which extend pins or screws 47 provided at their lower ends with heads 48 that are received in the extensions 35, 36 of the openings 33, 34 respectively. The screws 47 pass through the disk 38, and their heads 48 have their upper surfaces made perfectly smooth to fit tightly against the corresponding surface of the disk, to prevent leakage at this point. The upper ends of these pins screw into a cylinder or sleeve 49, the lower surface of which is drawn to a tight joint with the upper surface of the disk 38, by the action of said 15 pins or screws 47. Within the space surrounded by the sleeve 49 is located a valve member (shown in detail in Fig. 5) comprising a cylindrical body 50 of sheet metal or other relatively thin material, divided 20 into somewhat elastic tongues by longitudinal slots 51, a bottom plate 52 having a central perforation to register with the central port 39 of the disk 38, and an outwardly-extending top flange 53. This flange is 25 adapted to engage, or at least extends over, an inwardly-extending flange 54 at the lower end of a member 55 which has an external screw-thread to fit an internal screw-thread on the sleeve 49. Said member 55 also has 30 an annular top plate or ring 56 provided with holes 57 leading to the interior of the valve member body 50. From the inner edge of said ring 56 extends downwardly a cylindrical portion 58 provided with vertical 35 teeth 59 on its inner wall. At the lower end of said portion 58 is a plate 60, and below the same is a round head 61, of inverted T-shape in axial section (Fig. 1). Upon this head is adapted to be slipped 40 laterally, the upper slotted end 62 of another valve member (Figs. 10 and 12), which is thus connected to move in unison with the member 55 under normal conditions, but may be readily connected and disconnected 45 in assembling and dismembering the device. This valve member has a stem 63 extending through the central opening in the bottom plate 52, and in guiding engagement therewith, said stem being fluted as shown 50 in Fig. 6 so as to enable it to engage the edges of said opening and yet leave passages for the water as referred to below. The lower portion of the stem 63 is screw-threaded and extends through the central port 39 55 of the disk 38, with a sufficient clearance to give a sliding fit to the upper portion 64 of a nut 65, along the wall of said port 39. This upper portion 64 is cut off on two sides, as shown in Figs. 2, 3, and 6, so as to form two longitudinal passages which communicate at all times with some of the longitudinal passages which the flutes of the stem 63 form through the plate 52, see Figs. 1 and 6. The nut 65 has a head of hexagonal or other suitable form, located below the 60 disk 38, and a flange or plate 66 adapted for water-tight engagement with the lower face of the disk 38, at the recess 40 thereof. The nut also has notches 67 for the reception of cotter pins which would also 65 pass through holes 68 (Fig. 7) extending through the stem 63, preferably at right angles to each other, and one of them shifted relatively to the other, in an axial direction, a distance which is an odd multiple 70 of one-half the pitch of the thread. Thus, if the notches 67 are 60° apart, adjustments of 15° could be made by using one or the other of the holes 68 for the insertion of the cotter pin.

75 A coiled spring 69 bears against the top plate 56 and against a plate or washer 70 engaging the bottom plate 52, with sufficient strength to hold the valve member Fig. 5 closed under the conditions set forth hereinafter. The elasticity of the body 50 enables the flange 53 to be sprung into the normal position shown in Fig. 1, or to be withdrawn from connection with the member 55.

80 The teeth 59 of the member 55 are fitted between similar teeth on a member 71 constructed like a gear wheel and having a sliding connection (in an axial direction) with the member 55. Said toothed member 71 is connected rigidly with a handle 72, having a squared shank 73 on which said member 71 is fitted (Fig. 4), a screw 74 serving to secure said member in position. The handle 72 extends through a stuffing box 75 containing packing 76 and a gland 77. A 85 nut 78 holds these parts in position.

90 In connection with the handle 72, I employ an indicator which may be of the following construction: The upper casing member 46 has a flange 79 near its bottom, said flange extending over the inner edge of an annular indicator plate 80 bearing suitable words such as Shut, Cold, Mix, and Hot, see Fig. 4. To properly position said indicator, its inner edge is provided with a notch 81 to receive a pin 82 projecting from a suitable portion of the lower casing member, say the spud 32.

95 The operation is as follows: Fig. 1 shows the valve closed, the member 55 being 100 screwed as far as it will go into the sleeve 49, so that said member 55 presses the washer 70 and the valve member plate 52 firmly down toward the disk 38, the bottom plate 52 thus closing the hot water inlet 41; in 105

this position of the parts the cold water may indeed find its way along the fluted stem 63 to the lower surface of the portion 62, but can not flow any farther, since said lower surface is in tight engagement with the washer 70, which in turn is in tight engagement with the plate 52, the latter itself being in tight engagement with the upper surface of the disk 38. The handle 72, of course, has its actuating end in registry with the word Shut of the indicator ring or plate 80. The handle has been inserted originally in such a way that it will point to Shut when the member 55 is screwed in fully. Now suppose that we turn the handle slightly toward the word Cold. The interlocking of the teeth 59 with those of the member 71 compels the member 55 to turn with the handle 72, yet as the teeth of one of these members may slide lengthwise on those of the other member, the threaded member 55 can move axially or upward at the same time that it turns with the toothed member 71. This lifting movement carries the parts to a position of the character indicated in Fig. 2; that is to say, the lower face of the portion 62 is carried away from the washer 70, so that a passage is opened for the cold water, along the flutes of the stem 63, to the chamber above the washer 70. The coiled spring 69 is strong enough to prevent the pressure of the hot water (acting through the port 41) from raising the valve member 50, 52, 53 from the disk 38. Under the circumstances just described, therefore, only cold water will pass into the chamber above the washer 70, such cold water escaping upwardly through the holes 57 and then passing downwardly between the shell of member 46 and the outer surface of member or sleeve 49, then passing through the port 42 and opening 43 into the compartment 25 and through the spud 37 to the place of use. Suppose the handle 72 is then turned farther in the same direction (anti-clockwise), toward the word Mix. At a certain point of the further lifting movement thus given to the member 55, the valve member 50, 52, 53 will be raised, either by the engagement of the top flange 53 by the bottom flange 54 of the member 55, or (and this will generally be preferable), by the engagement of the upper end of the nut portion 64 with the bottom plate 52. It will be obvious that by properly dimensioning the parts, one or the other of these ways of lifting the member 50, 52, 53 will be obtained, as desired. I generally prefer to lift by the action of the nut portion 64 for the reason that the flange 53 is small and therefore liable to become worn or damaged if employed to receive the lifting strain. As soon as the bottom plate 52 is thus lifted, the port 41 is uncovered so that hot water can pass upwardly to the chamber surrounded by the sleeve 49, such hot water passing through the slots 51 and thus reaching the holes 57, from which it passes to the outlet in the same manner as described above with reference to the path of the cold water. The cold water will no longer need to pass through the plate 52 (although a small portion of it will still follow this path), but most of the cold water will flow between the disk 38 and the lower face of the plate 52, and then up and inwardly through the slots 51, mixing with the hot water and following the same path from the interior of the body 50 to the outlet spud 37. This mixing position is shown in Fig. 3. Upon turning the handle 72 still farther in the same direction, toward the word Hot, the upward movement of the member 55 will continue until it is arrested by the engagement of the plate 66 on the nut 65 with the lower surface of the disk 38, at the recess 40 of said disk. Inasmuch as such engagement is of a watertight character, the cold-water passage through the central port 39 will thus be closed, and from that moment on only hot water will be delivered through the spud 37.

Fig. 1 shows the vertical or axial dimension of the engaged portion of the toothed member 71 smaller than the corresponding dimension of the threaded flange 45. With this arrangement, it is possible to first screw the member 55 down fully, before applying the member 46, then screw the said upper casing member 46 but slightly on the lower casing member and then withdraw the toothed member 71 from engagement with the teeth 59 by an upward pull on the handle, until the upper face of said toothed member 71 engages the lower surface of the boss 83 on the upper casing member 46. Owing to the special relation of dimensions above referred to, the clearance between the lower surface of the boss 83 (with the member 46 almost fully unscrewed from the member 20, but still in threaded engagement therewith) and the upper surface of the member 55 (with the latter in the lowermost position, as in Figs. 1 and 8) will be greater than the vertical or axial dimension of the toothed member 71, so that the said member 71 can be disengaged from the member 55 while the members 20 and 46 still remain connected. The handle 72 thus being free, can be turned on its axis (without affecting the member 55) until the actuating end of the handle stands over the word Shut. Then the handle will be moved down to bring the toothed member 71 into engagement with the teeth 59 of the member 55, and thereupon the upper casing member 46 would be screwed down fully, to the position shown in Fig. 1. It will also be noted that the handle 72 is made with a bend of smooth curvature, and that the gland 77 has a curved inner

surface in engagement with the handle; I am thus enabled to make the handle in one piece and yet introduce and withdrawn it readily when desired, after unscrewing the 5 upper member or bonnet 46. While the bonnet is screwed down, however, the handle cannot be removed, since the means (screw 74) holding the handle is located within the casing of the appliance. The bonnet can be 10 removed only with the aid of a special large wrench such as is not readily available to the casual sneak thief. The nut 78 likewise cannot be removed unless the bonnet is first lifted off and the handle withdrawn. Theft 15 of the exposed parts of the appliance is thus rendered difficult.

In some cases it may be desirable to use the spud 31 for connection with the hot water supply, and the spud 32 as a cold 20 water inlet. To enable this to be done readily, I have provided the disk 38 with an additional port 42', similar to the port 42, and located symmetrically thereto. In the position illustrated, this port 42' lies on a solid 25 portion of the partition 22, and is closed, being in watertight engagement with said partition. When it is desired to use spud 31 for the hot water connection, and spud 32 for cold water, the upper casing member 46 30 will be screwed off, the disk 38 lifted together with the parts supported thereon until the heads of the screws 47 are clear of the partition 22, the disk with said parts would then be given a half-turn about its 35 axis, and after replacing the disk in this new position, with the screw heads 48 in the extensions 35, 36 of the ports 33, 34 respectively, the upper member 46 would be screwed down again. In this new assembly, 40 the port 42' will be in the position previously occupied by the port 42, and the port 41 will exchange positions with the recess 40. That is to say, the recess 40 will now 45 communicate with the port 34, the port 41 with the port 33, and the port 42' with the port 43, while the port 42 will register with, and be closed by, a solid portion of the partition 22.

It will be noted that in taking the apparatus apart there is no need of disturbing the lower casing member 20 or the connections made with its spuds 31, 32, and 37, and that after unscrewing the upper member or bonnet 46 the disk 38 may be lifted off with the parts supported thereon, as has been stated above.

In the form of my invention illustrated by Figs. 8 to 12, the screws 47 secure a sleeve 49' similar to the sleeve 49 but having its internal thread continued farther down. The upper portion of this internal thread co-operates with the external thread on the member 55', of substantially the same construction as the member 55. The top plate 56' however is not relied upon to fur-

nish a passage for the water, but has a screw-threaded opening to receive a screw 84, for a purpose to be stated presently. In order that the position of the screw 84 may be adjusted if required, I have shown two 70 openings 85, located at about 30° from the opening in which the screw 84 is placed, and also threaded to receive said screw; these extra openings 85 however may be omitted. When they are used, they form passages for 75 a small portion of the water, but the main flow of the water is through a different path, as will be explained below. The separable connection at 61, 62 is the same as in the first form of my invention, but the stem 80 63' is of a diameter to pass with a sliding fit through the central port 39 of the disk 38, and is made with spiral grooves through which, when the head 62 is raised, water may pass from the recess 40 to the chamber above 85 the disk 38. It will be noted that in this form of my invention the lower surface of the head 62 comes into sealing engagement with the upper face of the disk 38, the bottom plate 52' of the valve member body 50' 90 in this case controlling only the port 41 through which hot water passes to the chamber above the disk 38. The outwardly-extending top flange 53' of this valve body is adapted to be engaged by the inwardly extending flange 86 at the lower portion of a member 87 screwing into the sleeve 49', below the member 55'. From said member 87 a flange or short tubular extension 88 projects upwardly, at the same distance from the axis as the screw 84, and this tubular extension has a cut-out portion 89 (Fig. 9) so that the member 55' may be given a limited movement before the screw 84 will come 100 against the end of the cut-out 89 and then take along the member 87. A water passage is formed as follows from the chamber surrounded by the sleeve 49' to the port 42: Water entering such chamber through the port 39 will pass out through the slits 51' of the body 50' into an annular chamber between said body and the member 87, and then outwardly through slits 90 at the lower portion of said member, thus reaching another annular chamber 91 between the members 87 and 49', and finally out through slots 92 into the outer annular chamber between the sleeve 49' and the bonnet or upper casing member 46, said slots 92 being in the lower portion of the sleeve 49'. The other parts 110 of this construction are the same as in the form of my invention first described.

The operation of the second form of my invention is as follows: Fig. 8 shows the valve closed. If now the handle 72 and the member 55' are turned toward the open position, said member 55', for about one-fourth of a revolution, will turn without taking along the member 87, the screw 84 traveling (anti-clockwise in Fig. 9) in the slot or 120 130

cut-out 89. The head 62 is lifted off the disk 38, owing to the upward movement of the member 55', and thus cold water will pass from the recess 40 to the outlet 42, through the passage described above. The bottom edge of the tubular member 87 will press the plate 52' down to hold the inlet port 41 closed at this stage of the operation. As the handle 72 is turned farther toward the open position, the screw 84 will take the member 87 along, causing this member to rise, so that the flange 86 will engage and lift the flange 53', thereby insuring the opening of the inlet port 41, although this opening will really occur, by the pressure of the hot water, as soon as the lower end of the member 87 rises from the bottom flange 52'. In the closed position of the valve (Fig. 8) the head 62 contributes to hold the plate 52' seated. The flanges 86 and 53' might be omitted. As soon as the plate 52' is lifted as described, a mixture of hot and cold water will pass to the outlet 42. A further turning of the handle 72 toward the open position will bring the plate 66 at the top of the nut 65 against the lower surface of the disk 38, to shut off the supply of cold water, while hot water will continue to pass through the port 41, as in the form of my invention first described.

It will be noted that the head 62 which closes the discharge end of the cold water inlet 39 has a rotary connection with the member 55 or 55' which presses said head toward its seat. Thus the head 62 will at first turn in unison with the member 55 or 55' but as soon as the head engages its seat but lightly, friction will be sufficient to stop rotation of the head, and the member 55 or 55' will from that moment on rotate alone, but the head 62 will still be pressed down axially. By this construction I prevent the head 62 from grinding its seat. Similarly, the plate 52 is rotatably connected with the spring 69 and with the member 55, so that the said plate will not grind on its seat, but will allow the member 55 and the spring 69 to turn without rotating the plate 52, as soon as the latter engages its seat. The same remark will apply to the plate 52' and to the member 87 of the second construction described above.

The disk 38 is preferably made of relatively compressible material, such as hard rubber or Babbitt metal, so that the clamping action of the two casing members 20, 46 will readily produce tight joints at both faces of said disk.

The disk 38 has two inlet ports, 39 and 41, of which the port 39 is controlled, at the top, by the valve member or head 62, and, at the bottom, by the valve member 66 moving in unison with said head. The other port, 41, is controlled by the separately movable valve member 52 or 52', and is seated

when the head 62 seals the upper or discharge end of the inlet 39. The spring 69, in the first form of my invention, and the member 87, in the second form, constitute holding means for keeping the valve member 52 or 52' seated while the valve member or head 62 moves to a certain distance from its seat. The parts 54 or 64, in the first form of my invention, and the part 84, in the second form, constitute relieving means operated simultaneously with the movement of the valve member or head 62 beyond such distance from its seat, for stopping the valve-seating action of said holding means.

Some of the features of my invention are applicable to valves other than mixing valves, as will be evident from the appended claims.

Various modifications may be made without departing from the nature of my invention as defined in the appended claims.

I claim:

1. In a device of the character described, a valve casing having a chamber with two inlets and an outlet, a movable valve member controlling one of said inlets, rotary actuating means for pressing said valve member toward its seat, said means being held to move in unison with the valve member toward and from its seat, but being connected with said member in such a manner as to permit rotation of the actuating means relatively to the valve member whereby as soon as the latter is seated lightly, it will cease to turn, thus preventing a grinding action of the valve member on its seat, a separately movable member controlling the other inlet, rotatable holding means for keeping the second-named valve member seated while the first-named valve member moves to a certain distance from its seat, and relieving means, operated simultaneously with the movement of said first-named valve member beyond such distance from its seat, for stopping the valve-seating action of said holding means.

2. In a device of the character described, a valve casing having a chamber with two inlets for the admission of different fluids and an outlet, a movable valve member controlling one of said inlets, a separately movable valve member controlling the other inlet and opening in the same direction as the first-named valve member, and held seated by the pressure of the first-named valve member when the latter seals the inlet it controls, means for operating the first-named valve member, means for keeping said second-named valve member seated while the first-named valve member moves to a certain distance from its seat, relieving means, operated simultaneously with the movement of said first-named valve member beyond such distance from its seat, for stopping the valve-seating action of said holding means, and a third valve member, connected to share the

motion of the first-named valve member toward and from the inlet controlled thereby, and arranged to seat on the side of the inlet opposite to the side on which the first-named member seats, the distance between the first and third valve members, and the distance between their seats, being so proportioned that the third valve member will become seated only some time after both the first and the second valve members have become unseated.

3. In a device of the character described, a valve casing having a chamber with two inlets and an outlet, a movable valve member controlling one of said inlets, rotary actuating means for pressing said valve member toward its seat, said means being held to move in unison with the valve member toward and from its seat, but being connected with said member in such a manner as to permit rotation of the actuating means relatively to the valve member whereby as soon as the latter is seated lightly, it will cease to turn, thus preventing a grinding action of the valve member on its seat, a separately movable member controlling the other inlet, rotatable holding means for keeping the second-named valve member seated while the first-named valve member moves to a certain distance from its seat, relieving means, operated simultaneously with the movement of said first-named valve member beyond such distance from its seat, for stopping the valve-seating action of said holding means, and a third valve member, connected to share the motion of the first-named valve member toward and from the inlet controlled thereby, and arranged to seat on the side of the inlet opposite to the side on which the first-named member seats, the distance between the first and third valve members, and the distance between their seats, being so proportioned that the third valve member will become seated only some time after both the first and the second valve members have become unseated.

4. The combination of a valve casing having two diametrically opposite inlets at equal distances from its axis, and an outlet, a valve plate having differently located ports adapted to register at the same time with the respective ports of the casing, said valve plate being reversible by turning it about said axis, whereby either port of the valve plate may be made to connect with one inlet or the other, and means for controlling the passage of fluid through said plate.

5. The combination of a valve casing having two inlets on diametrically opposite sides of its axis, and an outlet, a valve plate having a port at a distance from such axis, to connect with one of said inlets, and a central port with a recess adapted to connect with the other inlet, said valve plate being reversible by turning it about said axis, whereby either port of the valve plate may be made to connect with one inlet or the other, and means for controlling the passage of fluid through said plate.

6. The combination of a valve casing having two inlets on diametrically opposite sides of its axis, and an outlet, a reversible valve plate provided with two passages the intake ends of which are adapted to register with said inlets in either position of the valve plate, while the discharge ends of said passages have different distance relations to said axis, and separate valve members controlling said discharge ends.

7. The combination of a valve casing having two inlets and an outlet, a valve plate adjustable for setting it in two different positions by turning it about its axis, said valve plate being provided with two passages the intake ends of which are adapted to connect with said inlets in either position of the valve plate, while the discharge ends of said passages have different distance relations to said axis, and separate valve members controlling said discharge ends.

8. The combination of a valve casing having two inlets and an outlet, a valve plate adjustable for setting it in two different positions by turning it about its axis, said valve plate being provided with two passages the intake ends of which are adapted to connect with said inlets in either position of the valve plate, while the discharge ends of said passages have different distance relations to said axis, and separate valve members controlling said discharge ends, and carried by said plate so as to preserve their position relatively thereto in either setting of the plate.

9. The combination of a separable valve casing, a ported plate located removably within said casing, and port-controlling means mounted on said plate movably and carried thereby so that said plate may be removed from the casing together with such port-controlling means without disturbing their relative position.

In testimony whereof I have signed this specification.

GROVER S. EBLE.
